UNITED STATES PATENT OFFICE.

HANS GUENTHERMANN, OF MOUNT VERNON, NEW YORK.

DESIGN FOR A PLATE OR SIMILAR ARTICLE.

50,618.

Specification for Design.

Patented Apr. 17, 1917.

Application filed February 21, 1917. Serial No. 150,277. Term of patent 3½ years.

To all whom it may concern:

Be it known that I, HANS GUENTHERMANN, a citizen of the German Empire, and resident of Mount Vernon, county of Westchester, and State of New York, have invented a new, original, and ornamental Design for a Plate or Similar Article, of which the following is a specification, reference being had to the accompanying drawing, forming part thereof, which drawing is a plan view of a plate or similar article, illustrating my new design.

I claim:

The ornamental design for a plate or similar article, as shown.

HANS GUENTHERMANN.
